DESIGN FOR A DRAWER PULL

Robert W. Gane, Jamestown, N. Y., assignor to
Chautauqua Hardware Corporation, Jamestown, N. Y.

Application July 25, 1947, Serial No. 140,518

Term of patent 3½ years

(Cl. D10—8)

To all whom it may concern:

Be it known that I, Robert W. Gane, a citizen of the United States, residing at Jamestown, in the county of Chautauqua and State of New York, have invented a new, original, and ornamental Design for a Drawer Pull, of which the following is a specification, reference being had to the accompanying drawing, forming part thereof, and in which

Fig. 1 is a front elevational view of a drawer pull showing my new design;

Fig. 2 is a top edge elevational view; and

Fig. 3 is a side edge elevational view.

I claim:

The ornamental design for a drawer pull, substantially as shown.

ROBERT W. GANE.
